UNITED STATES PATENT OFFICE.

JOHN F. McCANNA, OF CHICAGO, ILLINOIS, ASSIGNOR TO McCORD & COMPANY, OF CHICAGO, ILLINOIS, A CORPORATION OF NEW JERSEY.

FORCE-FEED LUBRICATOR.

No. 861,757.

Specification of Letters Patent.

Patented July 30, 1907.

Application filed January 5, 1905. Serial No. 239,691.

To all whom it may concern:

Be it known that I, JOHN F. McCANNA, a citizen of the United States, residing at Chicago, in the county of Cook and State of Illinois, have invented certain 5 new and useful Improvements in Force-Feed Lubricators, of which the following is a specification; reference being had therein to the accompanying drawing.

This invention relates to improvements in that class 10 of force feed lubricators which are adapted to deliver oil from a reservoir to one or more bearings or other working parts located at different points, such as the cylinders and bearings of automobile motors, engines and other mechanisms.

The invention consists of the combinations and arrangements of parts hereinafter particularly described and then pointed out in the appended claims.

In the accompanying drawings, which illustrate one embodiment of the invention—Figure 1 is a longitudinal sectional view partially in elevation, showing the cover 20 slightly elevated above the reservoir; Fig. 2 is a section on the line 2—2 of Fig. 1; Fig. 3 is a section on the line 3—3 of Fig. 2, one end of the reservoir being broken away; and Fig. 4 is a horizontal section through one set of pumps being taken on the line 4—4 of Fig. 2.

25 Referring to the drawings, 10 indicates a suitable oil reservoir of any preferred size and shape. In the present instance the reservoir is rectangular in form and has a removable cover 11 secured in position by screws 12 or other means.

30 One of the novel features of the invention relates to an improved mechanism located within the reservoir and adapted to transmit motion from a suitable source of power, such as the apparatus being lubricated, to the pumps which are also located in the reservoir. This 35 driving mechanism comprises the following construction. A shaft 13 is suitably journaled on and passes through one of the walls of the reservoir, entering a bearing 14 provided therefor in the reservoir. As shown in Fig. 2, one end of the shaft 13 extends outside 40 of the reservoir and is designed to receive motion through the medium of any suitable mechanism from the source of power. The shaft 13 is provided within the reservoir with a worm 15 which engages and drives a worm gear 16 rotatably mounted on a stub shaft 17 suitably secured to one end of the reservoir. An eccentric 18 is 45 also loosely journaled on the stub shaft 17 and is fixed to the worm gear 16, as by means of a pin 19.

A rocker shaft 20 is journaled in bearings 21 at the ends of the reservoir and one of these bearings, as shown 50 in Fig. 1, opens through the end of the reservoir, such opening being closed by a screw-plug 22. Motion is communicated to the rocker shaft 20 by the eccentric 18 through the medium of a yoke 23 straddling the eccentric, as shown in Fig. 2, and fixed, as by means of a

set-screw 24, to the shaft 20. The yoke 23 may be of 55 the inverted U-shape shown. The shaft 20 is designed to communicate motion to the plunger of the pump located in the reservoir or where a plurality of pumps are employed to the plungers of all of such pumps. In the present instance I have shown a plurality of sets of pumps each of which sets comprises, as 60 shown in Fig. 2, a main pump 25 and an auxiliary pump 26. Three of such sets of pumps are shown and located at intervals along the shaft 20. The shaft 20 is provided at suitable points with rocker members comprising 65 opposite arms 27 and 28 each pair of which is carried by a sleeve 29 connected, as by a set screw 30, to the shaft. As shown in Fig. 2 where one set of pumps is shown in section the arm 27 projects into a slot formed in an extension 31 of the piston 32 of the main pump 25 while 70 the opposite arm 28 enters a slot in an extension 33 of the plunger 34 of the auxiliary pump 26. By reason of the construction described, it is obvious that as the eccentric 18 is rotated the shaft 20 will be rocked and through the medium of the arms 27 and 28 reciprocate 75 the plungers of the main and auxiliary pumps simultaneously and in opposite directions.

The driving mechanism, comprising the worm shaft and gear, eccentric and yoke, is within the reservoir and preferably located at one end thereof, as shown in Fig. 80 1. This arrangement greatly simplifies the mechanism for reciprocating the pump plungers and avoids the use of the usual extended eccentric shaft and co-operating yokes associated with each pump, and at the same time provides for the simultaneous operation of a plurality 85 of pumps.

In the construction described, each main pump 25 is designed to draw the oil from the reservoir and deliver the same through a suitable sight feed device to the associated auxiliary pump 26 which discharges the oil to 90 the part to be lubricated. To this end the body of the pump 25 is provided with an inlet 35 controlled by a suitable valve 36. A passage 37, provided with a check valve 38, leads from the pump 25 to a vertical tube 39 which enters an associated sight feed device, 95 designated as a whole by 40. After passing through the sight feed device, as hereinafter explained, the oil is conducted by a vertical tube 41 to the auxiliary pump 26 by an inlet 42 provided with a suitable valve 43. A discharge passage 44 leads from the pump 26 to 100 the part to be lubricated and is provided with a valve 45 designed to prevent the oil from flowing back into the pump after having been discharged. The valves 36 and 43 are limited in their movement by suitable stops, such as screws 46.

The sight feed devices 40 are carried by the cover 11 and are so arranged as to be disconnected from the inlet and outlet tubes 39 and 41 when the cover is re-

removed to permit of access to the mechanism within the reservoir for purpose of disassembling or repairs. Each of these sight feed devices consists of a glass tube 47 having a cap 48 and a base ring 49. The base ring 5 has a vertical flange 50 to receive the lower end of the glass and an internal shoulder 51 on which the glass rests. The base ring is also provided with an annular depending flange 52 extending through a suitable aperture in the cover 11. A disk 53 is located under 10 the cover 11 and provided with an upstanding flange 54 which receives the flange 52 of the ring 49. As shown in Fig. 3, the disk is provided with a pair of depending thimbles 55 one of which is threaded at its upper end and receives the upper end of the tube 15 39 while the other thimble receives the upper end of the tube 41. A tube 56 screws into the end of the threaded thimble 55 and has its upper end bent downwardly so as to aline with the upper end of the tube 41. A screw 57 passes through the cap 48 and engages 20 a threaded aperture in the bent end of the tube 56. Suitable packing rings 58 are provided for the sight feed device to prevent leakage of the lubricant. By reason of the engagement of the threaded end of the tube 56 with the disk 53 and the screw passing through 25 the cap 48 and engaging the tube 56 each sight feed is securely clamped to the cover; and owing to the telescopic connection with the tubes 39 and 41, provided by the thimbles 55, the sight feed devices may be disconnected from the said tubes merely by removing 30 the cover. Each sight feed device is provided with a suitable air inlet which may pass, for example, through the cap 48, as at 59. Each sight feed device 40 serves to indicate the rate of feed of the associated set of pumps, the dropping of the oil from the tube 35 56 being visible through the glass of the sight feed.

The operation of the device will be readily understood. On the suction stroke of the plunger 32 of each main pump oil is drawn from the reservoir and then discharged by the plunger past the valves 38 to 40 the tube 39. As the oil rises in the tube 39 it passes into the tube 56 and drops from the bent end of the latter into the tube 41. On the suction stroke of the plunger of the auxiliary pump 26 the oil in the tube 41 is sucked in past the valve 43 and then discharged 45 by way of the passage 44 to the part to be lubricated. The pump 26 is preferably of greater capacity than the pump 25, and as the former pump is able to take care of a greater supply of oil than is delivered thereto by the pump 25, on the suction stroke of the plunger 50 of the auxiliary pump, air is drawn in through the inlet 59 and enters with the oil past the valve 43 to the pump 26. By reason of this charge of air which is drawn in by the auxiliary pump and compressed against the resistance of the gravity valve 45, the oil 55 is forced under the pressure of such compressed air to the bearing.

While the stroke of the plunger of the auxiliary pump 26 is constant, the stroke of the plunger 32 of the main pump is designed to be adjusted so that the 60 quantity of oil fed to the auxiliary pump and consequently to the bearing may be varied as desired. For this purpose an adjustable abutment is located in the slot of the extension 31 of each of the pumps 25 in such position as to be engaged by the arm 27 65 during its movement in one direction. This abut-

ment may take the form of a shoulder 60 at the lower end of a stem 61 in threaded engagement with the extension 31 and passing upwardly through a suitable aperture in the cover 11. By turning the stem 61 the shoulder 60 may be suitably adjusted to vary 70 or eliminate lost motion between the arm 31 and the pump plunger, to vary the stroke of such plunger. The shoulder 60 prevents the stem 61 from being disengaged from the plunger; and as the upper end of the stem 61 projects above the cover the reciprocation 75 of such stem will indicate the stroke of the pump.

As shown in Figs. 2 and 4, the bodies of the main and auxiliary pumps are made of single castings connected as by a screw connection 62 and each set of pumps is removably secured to the reservoir, as by 80 a nut 63. This is material only in that it facilitates the assembling and disassembling of the parts. If, for example, it is desired to remove the pumps from the reservoir, after the cover 11 is removed, it is only necessary to loosen the set-screws 24 and 30, to free 85 the yoke 23 and arms 27 and 28 from the shaft 20, remove the screw plug 22 and withdraw the shaft 20. Then by removing the nuts 63 each set of pumps may be withdrawn bodily from the reservoir together with the associated actuating arms 27 and 28. 90

Having described my invention what I claim is—

1. In a device of the class described, the combination with a reservoir and a pair of coöperating pumps therein, a rocker member within the reservoir and provided with opposite arms to reciprocate the pump plungers, a shaft 95 to which the said member is fixed and means for rocking the shaft.

2. In a device of the class described, the combination with a reservoir and a plurality of pairs of coöperating pumps therein the plungers of which are provided with slotted extensions, a rocker member associated with each pair of pumps and provided with opposite arms entering the slots of the plungers thereof, a shaft on which the rocker members are fixed, and an eccentric for rocking the said shaft. 100

3. In a device of the class described, the combination with a reservoir and a pair of coöperating pumps located therein, of a rocker shaft in the reservoir and located between the pumps, opposite arms on the shaft to reciprocate the pump plungers, and means to operate the shaft. 105

4. In a device of the class described, the combination with a reservoir and a pair of coöperating pumps located therein, of a rocker shaft between the pumps, opposite arms on the shaft to reciprocate the pump plungers, an eccentric, means to operate the shaft, and means carried by the plunger of one of the pumps to vary the stroke thereof. 110

5. In a device of the class described, the combination with a reservoir and a pair of coöperating pumps located therein, of a rocker shaft between the pumps, opposite arms on the shaft to reciprocate the plungers of the main and auxiliary pumps simultaneously in opposite directions, an eccentric means to operate the shaft, and a stem movable with the plunger of the main pump and extending outside of the reservoir and providing an adjustable abutment in the path of the arms coöperating with such pump. 115

6. In a device of the class described, the combination with a reservoir and a plurality of sets of pumps therein, each set comprising a main and an auxiliary pump, a rocker shaft in the reservoir between the main and the auxiliary pumps, opposite arms on the shaft coöperating with the pumps, and means to operate the shaft. 120

7. In a device of the class described, the combination with a reservoir, a removable cover secured only to the reservoir, and a pump located in the reservoir, of a sight feed device carried by the cover and disconnected from its associated pump by the removal of the cover. 125

8. In a device of the class described, the combination with a reservoir, a removable cover therefor, and a pump

located in the reservoir, of a sight feed device carried by the cover, and a tube leading from the pump and having telescopic connection with the sight feed device, the sight feed device being disconnected from the tube by the removal of the cover.

9. In a device of the class described, the combination with a reservoir, a removable cover therefor, a main and an auxiliary pump in the reservoir, of a sight feed device carried by the cover, a tube leading from the main pump 10 to the sight feed device, and a tube leading from the sight feed device to the auxiliary pump, both of said tubes having telescopic connection with the sight feed device, the sight feed device being disconnected from the tubes by the removal of the cover.

15 10. In a device of the class described, the combination with a reservoir, a removable cover therefor, a pair of co-operating pumps in the reservoir, means for reciprocating the pump plungers, of a sight feed device carried by the cover and through which the oil passes from one pump to 20 the other, the said sight feed device comprising a glass, a cap, a ring located under and engaging the cover and having a pair of depending thimbles one set of which is threaded, a tube in the glass engaging the threaded thimble and having its upper end terminating in alignment with the 25 other thimble, a screw passing through the cap and engaging the upper end of the tube, and tubes associated with the pumps and having telescopic connection with the

thimbles, whereby the sight feed device is adapted to be disconnected from the pumps by the removal of the cover.

11. In a device of the class described, the combination 30 with a reservoir, a removable cover, and a pump and driving means therefor located in the reservoir, of a sight feed device mounted on the cover, a discharge tube for the pump loosely connecting with the sight feed device, and means for varying the stroke of the pump plunger passing 35 freely through the cover, whereby when the cover is removed it is disengaged from the said means and the sight feed device is disconnected from the tube.

12. In a device of the class described, the combination 40 with a reservoir, a removable cover, and a pump and driving means therefor located in the reservoir, of a sight feed device mounted on the cover, a discharge tube for the pump having telescopic connection with the sight feed device and a stem connected with the driving means for varying the stroke of the pump plunger and extending 45 loosely through the cover, whereby when the cover is removed it is disengaged from the said stem and the sight feed device is disconnected from the tube.

In testimony whereof I affix my signature in presence of two witnesses.

JOHN F. McCANNA.
